MANNEQUIN LIMB

Joseph R. Dusko, Youngstown, Ohio

Application December 15, 1945, Serial No. 635,190

2 Claims. (Cl. 46—163)

1

This invention relates to a method of making and repairing mannequins and more particularly to the construction of the shoulders, wrist and waist joints thereof.

The principal object of the invention is the provision of a method of making an improved joint construction as used in mannequins.

A further object of the invention is the provision of a mannequin construction incorporating structural members and surface members and means effectively joining the two together to form an unbreakable, integral unit.

A still further object of the invention is the provision of a mannequin construction incorporating joint structures firmly uniting the papier-mâché body of the mannequin to a metallic structural supporting member and joint means.

The method of making and repairing mannequins shown and described herein has been devised to provide a more substantial structure than has heretofore been possible with the various constructions heretofore known in the art. It is well known that many mannequins of various sizes and shapes are employed in retail establishments for the display of wearing apparel. It is also known that these mannequins are primarily formed of hollow papier-mâché body parts and that the various limbs and body parts are removably affixed to one another so that the mannequin can be adjusted as to various positions and postures and straight or curved arms substituted or interchanged so that the merchandise may be more advantageously displayed thereon. It is also well known that these mannequins are frail and subject to considerable breakage particularly with respect to the sections thereof adjacent the joints by means of which the various body and limb portions are attached to one another. The present invention relates to a method of making and/or repairing mannequins to avoid breakage at or near the joint structures.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a plan view with parts broken away and parts in cross section illustrating the portion

2

of a mannequin and the construction of a joint structure therein.

Figure 2 is an enlarged cross sectional side elevation of a portion of an arm of a mannequin illustrating the method of making and/or repairing the same.

Figure 3 is an end elevation of the joint portion of the mannequin illustrated in Figure 2.

By referring to the drawings and Figure 1 in particular, it will be seen that a mannequin is generally indicated by the numeral 10, a lower portion 11 being attached thereto as at a waist joint 12, and an arm portion 13 affixed to a shoulder portion 14 of the mannequin by a joint construction including a bifurcated structural member 15 located within the body portion 10 of the mannequin and terminating in a face plate 16 which is slotted to enable it to receive a ball joint construction 17 attached to the arm 13.

In Figures 1 and 2 of the drawings the arm 13 will be seen to comprise a hollow arm structure, preferably formed of papier-mâché as is customary in the art, and having the added features of an internally positioned metallic structural assembly 18 in the form of a pair of rods spaced apart and retained in spaced relation as by means of a bracing member 19 which is welded or otherwise affixed to the rods 18. The uppermost end sections of the rods 18 are welded or otherwise affixed to a plate 20, and the ball joint assembly 17, heretofore referred to, projects therefrom so that it may operatively engage a suitable mounting slot or cavity in the face plate 16 in the shoulder construction 14 of the mannequin 10. The upper end section of the hollow papier-mâché arm 13 is filled with a wooden disc 21 which is located immediately adjacent the plate 20. It will be observed that the rods 18 extend through the wooden disc 21 by way of openings 22 formed therein.

In forming the construction in accordance with the invention, a tubular section of screen 23 is positioned about the end of the arm 13 and within a cut-away section 24 of the layers of papier-mâché. A plurality of tacks 25 are driven through the screen 23, the papier-mâché layers of the arm 13 and into the wooden disc 21 thereby firmly uniting the screen 23, the papier-mâché layers of the arm 13 and the wooden disc 21. A mold is then positioned to provide for the application of a metal cap 26 which is preferably of solder and poured so that one section thereof engages the outer edges of the plate 20 and the other section thereof extends over the tacks 25 and the screen 23 a substantial distance back onto the

hollow arm 13. The papier-mâché of the arm 13 is thereby firmly affixed to the end structure comprising the plate 20 and the wooden disc 21 and sealed thereto by the application of the poured metal cap 26. A plaster or plastic material fill 27 is then applied to the area of exposed screen and cut papier-mâché layers 24 to fill in satisfactorily between the cut end section and the inner end of the poured metal cap 26. When this is properly set, the exterior enamel finish customarily used in finishing mannequins is then applied over the entire joint structure including the plaster fill 27 and the metal cap 26. The resulting structure has been found to resist breakage unusually well, and as it is equally applicable in new constructions or in the repairing of broken mannequin joint structures, the invention is considered to relate to both.

It will be obvious to those skilled in the art of mannequin formation that the structure thus disclosed applying to the shoulder joint of the mannequin may be equally advantageously applied to the wrist joints, waist joints and other joints of a mannequin.

It will be obvious that the detailed disclosure as set forth in Figure 2 is used on both halves of the joint, that is, on the shoulder portion and the arm portion as illustrated in Figure 1 and indicated by the numerals 14 and 13, respectively. The same is true in its use in a wrist joint, the same construction being applied in opposed relation to both the hand section, if desired, and the wrist section. In this connection it is pointed out that it is sometimes customary in the mannequin art to apply solid hand portions and in this event the construction disclosed herein is applied only to the wrist end of the arm portion of the mannequin as well as to the other various joint structures of the mannequin.

It will thus be seen that a simple and efficient method of making and repairing a mannequin has been disclosed, which method may be advantageously used in re-working mannequins as well as in the formation of new mannequins. The structural members inserted within the hollow body and limb portions of the mannequin carry the stress of the mannequin structure, and as these stresses are conveyed directly to one another by the plate and face plate portions included in

the joint assemblies, there is little or no likelihood of the papier-mâché body portions being broken away from the joint structures as has heretofore been commonplace.

Having thus described my invention, what I claim is:

1. A mannequin limb including a hollow body section, a metallic supporting structure positioned therein, metallic end plates affixed to both ends of the said supporting structure and defining the ends of the said limb, joint means affixed to the said metallic end plates, nailer sections positioned immediately adjacent the said metallic end plates and inwardly therefrom, and means for attaching the end sections of the hollow limb to the said nailer sections and metallic end plates, said means comprising a layer of screen encircling each end section of the limb, fasteners driven through the screen and the material of the hollow limb and into the circumferential edge of the nailer section, and a metal cap encircling and overlying at least part of the screened section and enclosing the end of the hollow limb, and finishing material filling the surface area between the metal cap and the finished surface area of the said hollow limb.
2. In a mannequin having a plurality of body and limb portions removably affixed to one another, each of the said body and limb portions comprising a hollow member, a supporting structure positioned therein, end plates affixed to both ends of the said supporting structure and defining the ends of the said hollow member, joint means affixed to the said plates, nailer sections positioned adjacent the said plates and inwardly therefrom, and means for attaching the end sections of the hollow members to the said nailer sections and plates, said means comprising a layer of screen encircling each end section of the hollow member, fasteners driven through the screen and the material of the hollow member and into the circumferential edge of the nailer section, and a cap encircling and overlying at least part of the said screened section and enclosing the end of the hollow member and finishing material filling the surface area between the cap and the finished surface area of the said hollow member.

JOSEPH R. DUSKO.
